H. Linn.

Vibrating Propeller

A. I. Patented Nov. 16, 1858.

Witnesses,

G. F. Atton
J. B. DayInventor
Henry Linn

No. 201,115. Henry Linn, Patent No. 12,829. For Vibrating Propeller. Patented Nov. 16, 1858. A. I. - Made up of a series of bars, hinged together, and so arranged as to vibrate, as described, in combination with a propeller, which is either held or solid, substantially as shown.